UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

ELECTROLIER.

1,158,113.

Specification of Letters Patent. Patented Oct. 26, 1915.

Original application filed December 27, 1909, Serial No. 535,162. Divided and this application filed March 10, 1911. Serial No. 613,571.

To all whom it may concern:

Be it known that I, REUBEN B. BENJAMIN, a citizen of the United States, residing at Chicago, in the county of Cook and State of Illinois, have invented new and useful Improvements in Electroliers, of which the following is a full, clear, concise, and exact description, reference being had to the accompanying drawing, forming a part of 10 this specification.

My invention relates to electroliers having individual switches for the lamps carried by the various arms thereof, and has as its principal object the provision of a 15 device of this character, in which jarring of the lamps, due to the operation of the switches, is minimized.

It is a further object of my invention to provide an improved pull switch mechanism.

It is a considerable disadvantage in electroliers of the usual forms of construction that the switches for controlling the lamps are usually carried by the sockets themselves. This gives rise to a jarring effect upon the lamps, particularly when the switches are of the kind known as pull switches. This kind of switch is, however, in other respects a very convenient variety. 25 Now that the tungsten and other similar lamps have come into general use, this disadvantage has become the more important, since the filaments of these lamps are very delicate and a very little vibration injures 30 them. I remedy the above drawback by providing a plurality of pull switches, one for each arm of the electrolier, situated in the body of the electrolier, so that there is no chance of appreciable vibration being 35 imparted to the lamps.

In the accompanying drawing, I have shown an electrolier constructed in accordance with my invention, the device shown being the same, in its details, as that described in my Patent No. 1,016,317, dated February 6, 1912, of which this application is a division. It is to be understood, however, that, in other embodiments of my invention, the details of the electrolier may be 45 changed without exceeding the scope of my invention as defined in the appended claims.

In the drawings: Figure 1 is a partly sectional elevation of an electrolier construct-

ed in accordance with my invention; Fig. 2 is a plan of the switch-supporting base; 55 Fig. 3 is a detail sectional view, the section being taken on the line 3—3 of Fig. 2; and Fig. 4 is a detail sectional view, the section being taken on the line 4—4 of Fig. 2.

Referring now to the drawings, 10 is a 60 supporting plate or member adapted to be secured to the lower end of a conduit such as 11. To this plate are connected a plurality of lamp-socket-supporting arms 12, the connection being effected by securing L-shaped extensions 13 upon the ends of the arms 12 and connecting these extensions to the plate 10 by means of hollow rivets 14 passing through suitable holes formed in the supporting plate 10 and in the extensions 13. The hollow rivets 14 are of sufficient size to permit the passage therethrough of the conductors leading from the sockets and entering the electrolier through the hollow arms 12. To the lower side of the supporting plate 10 is secured, as will be hereinafter described, a switch-supporting base 22, the base being protected by an outer casing 16 which fits upon the plate 10 and is formed with a plurality of vertical recesses 65 15, through which the socket-supporting arms 12 extend outwardly. In order to impart a pleasing and finished appearance to the device, a hood 21 is mounted on the conduit 11, the hood being arranged to engage 70 20 over and close the upper end of the casing 16.

The switch-supporting base 22 is secured in place upon the lower side of the supporting plate 10 by means of screws 23 which 75 pass through the base and into the supporting plate. These screws also serve to secure in position upon the under side of the base 22, a bridge 24 to which the casing 16 is attached by means of a suitable thumb screw 80 25. Clamped between the bridge 24 and the under side of the base 22 is an insulating plate 26 which extends over the whole of the lower face of the base 22.

The base 22 is formed with an upper and 100 a lower annular recess, 27 and 28 respectively, in which are secured, by means of suitable rivets such as 29, conductor rings 30 and 31. The upper conductor ring 30 carries a binding terminal 31^a to which one of 105 the leading-in wires, entering through the

conduit 11, is secured. The lower conducting ring 31 carries a number of binding terminals 32, to one of which the other leading-in wire is secured. The other binding terminals 32 each receive the end of one of the conductors leading from the lamp sockets and extending through the arms 12 and hollow rivets 14. Upon the upper face of the base 22 are mounted a number of contact plates 33, one for each of the socket supporting arms 12. These contact plates are secured in place by means of screws passing through the base and entering terminal plates 34 upon the lower side thereof. These terminal plates carry binding terminals 35 each of which receives the end of a conductor leading from the respective lamp socket. To accommodate the conductors which are to be secured to the binding terminals 35, the base is formed with passages 36 extending therethrough and opening adjacent these binding terminals. The conductor ring 30 is provided with a plurality of spring contact strips 37 extending outwardly through suitable passages formed in the base 22, one of these strips being provided for each of the contact plates 33. These contact strips are adapted to be forced into contact with the plates 33 by means of triangular cams 38 mounted upon spindles 39 rotatably supported in suitable recesses of the base. When a contact strip rests upon one of the flat portions of its particular cam it remains out of contact with the corresponding contact plate 33, but when the cam is turned so that one of its angles bears against the contact strip, the latter is forced up against the contact plate 33. Electrical connection is thereby established between the conductor ring 30 and the particular contact plate 33, current being thereby enabled to flow from the leading-in wire to the conductor ring 30, thence to the particular contact plate 33, thence to the lamp and back to the conductor ring 31 and the other leading-in wire.

In order that the rotation of the cams 38 may be effected, a ratchet wheel 40 is mounted upon each of the spindles 39, each of these ratchet wheels having six teeth. Rockably mounted upon each spindle 39 is a lever 41 carrying a spring pawl arranged to engage the teeth of the adjacent ratchet wheel. To each of these levers is attached a flexible cord 42 by means of which the levers may be operated, the casing 16 being formed with suitable openings through which the cords 42 extend. Springs 43 are connected between the levers 41 and the support plate 10 to effect the return of the levers after a switch has been operated. It will thus be seen that a single pull on any one of the cords 42 will operate to switch the corresponding lamp either on or off, while a second pull will put the lamp into the reverse condition. The switches being supported in

the body of the electrolier, little or no vibration is imparted to the lamps carried by the arms 12, when the lamps are turned on or off. Besides this, the construction is a very simple one and very convenient in use. 70

Having thus described my invention, what I claim as new and desire to secure by Letters Patent, is:

1. In an electrolier, the combination with a central supporting plate arranged to be secured to the end of a conduit, of a plurality of lamp socket carrying arms secured upon said plate and extending radially therefrom, an insulating base mounted on the under side of said plate, and a plurality of pull switches, one for each of said lamp socket carrying arms mounted on said base and adapted to control the circuit of the lamp sockets carried on said arms, the pull means for these switches being located around the axis of the center support in positions corresponding to the positions of the various lamps whereby the operator may know which light will be lit when a certain pull is operated. 75 80 85 90

2. An electrolier comprising, in combination, a central supporting plate arranged to be secured upon the end of a conduit, a plurality of lamp socket supporting arms carried thereby and radially extending from said conduit, an insulating base secured on the under side of said supporting plate, and a plurality of pull switches mounted on said base, one for each of the sockets carried on said arms, and an inclosing cover for the base, the pull means for these switches being located around the axis of the center support in positions corresponding to the positions of the various lamps whereby the operator may know which light will be lit when a certain pull is operated. 95 100 105

3. The combination with a central support, of means for supporting a plurality of electric lamps thereon around the axis of said central support, and a plurality of pull switches, one for each of said lamps, all supported independently of the lamps by said central support, the pull means for these switches being located around the axis of the said central support in various positions corresponding to the positions of the various lamps, whereby the operator may know which light will be lit when a certain pull is operated. 110 115

4. A plural lamp fixture comprising means for supporting a plurality of lamps, a conducting member having a terminal connection for one of the main feed wires, and a plurality of terminal connections, one for each of the lamps, a second conducting member having a terminal connection for the other main feed wire, and a plurality of terminal connections, one for each of the lamps, and a plurality of switches, one located in each individual lamp circuit. 120 125 130 135 140

5. A plural lamp fixture comprising means for supporting a plurality of lamps, an annular conducting member having a terminal connection for one of the main feed wires, and a plurality of terminal connections, one for each of the lamps, a second annular conducting member having a terminal connection for the other main feed wire, and a plurality of terminal connections, one 10 for each of the lamps, and a plurality of

switches, one located in each individual lamp circuit.

In witness whereof, I have hereunto subscribed my name in the presence of two witnesses.
